UNITED STATES PATENT OFFICE.

WALTER O'BLAZA, OF CHICAGO, ILLINOIS.

DESIGN FOR A PALM-STAND.

57,145.

Specification for Design.

Patented Feb. 22, 1921.

Application filed March 5, 1920. Serial No. 363,578. Term of patent 7 years.

To all whom it may concern:

Be it known that I, WALTER O'BLAZA, a citizen of the United States of America, residing at Chicago, in the county of Cook and State of Illinois, have invented a new, original Design for a Palm-Stand, of which the following is a specification, reference being had to the accompanying drawing, forming part thereof.

The figure is a view in perspective of a palm stand, showing my new design.

I claim:—

The ornamental design for a palm stand, as shown.

WALTER O'BLAZA.
